OSCILLATION GENERATOR

Filed March 18, 1927

Inventor:
Charles J. Young,
by *Charles J. Young*,
His Attorney.

UNITED STATES PATENT OFFICE

CHARLES J. YOUNG, OF SCHENECTADY, NEW YORK, ASSIGNOR TO GENERAL ELECTRIC COMPANY, A CORPORATION OF NEW YORK

OSCILLATION GENERATOR

Application filed March 18, 1927. Serial No. 176,472.

My invention relates to oscillation generators, and particularly to oscillation generators of the polyphase type. It has for its purpose, among others, to provide an oscillation generator of this type in which the frequency of the oscillations produced is readily variable. It has for its further purpose to provide an oscillation generator which is adapted for the generation of polyphase currents of audio frequency in a more efficient and satisfactory manner than has heretofore been possible, and in which the audio channels are free from resonant or tuned circuits.

The novel features of my invention are set forth in the appended claims. My invention itself, however, both as to its organization and method of operation, together with further objects and advantages thereof, may be best understood by reference to the following description taken in connection with the accompanying drawing which illustrates an oscillation generator embodying my invention.

Referring to the drawing, 1 represents an electron discharge device which may be of the three element type which I employ as a generator of single phase oscillating currents. 2 represents an oscillatory circuit connected between the grid and the cathode and 3 the usual feed-back coil which is connected between the anode and cathode and which is inductively associated with the inductance of the oscillatory circuit 2. 4 represents a variable condenser connected in parallel with the oscillatory circuit 2 and which is used for the purpose of adjusting the frequency of the oscillator to desired values. 5 represents a second electron discharge device which I employ as an amplifier for the oscillations produced by the device 1. This device has its grid connected by a conductor 6 to the oscillatory circuit of the device 1. The cathodes of these electron discharge devices are supplied with heating currents through conductors 7 leading to a suitable source of potential 8. The anode potential for the oscillation generator 1 is supplied by means of a source of potential 9 through a circuit leading from one side of the cathode circuit 7 through the source 9,

conductor 10, radio frequency choke 11, feed-back coil 3, and stabilizing resistance 50 to the anode of the device 1. Likewise the anode potential for the amplifier 5 is supplied by means of the source 9 through a circuit including the conductor 10, radio frequency choke 12, conductor 13, branch circuits 14 and 15 to the anode of the device 5. Connected in parallel with the circuit 14 is a third branch circuit 16. The branch circuits 14, 15 and 16 comprise the output circuit of amplifier 5 and are made up of inductance, capacity and resistance of such values as to pass currents bearing a definite polyphase relation to each other. Thus, in the particular case shown the current which passes through the circuit 16 may lead the current flowing through the circuit 15 by 60 degrees, whereas that flowing through the circuit 14 will lag behind that flowing in the circuit 15 by 60 degrees. Connected in each of these circuits respectively are the primary windings of transformers 17, 18 and 19. Thus, it may be seen that by proper connection of the secondary windings of these transformers with respect to each other as conventionally shown in the drawing symmetrically related polyphase electromotive forces are produced in the secondary windings. It will, of course, be understood that there may be as many circuits 14, 15 and 16 as it is desired to have phases in the polyphase currents which are to be produced. 20, 21 and 22 are electron discharge devices which I employ as modulators. The cathodes of these devices are heated from the cathode circuit 7 and the grids of each of these devices are biased to a negative potential with respect to their respective cathodes by means of a source of potential 23 which is connected in the circuit leading from the cathode circuit 7 through the source 23, conductor 24, secondary winding of the transformer 25, the secondary winding of the transformers 17, 18 and 19 to the grids of the devices 20, 21 and 22, respectively. 26 represents a second oscillation generator which is connected in a circuit similar to that of the device 1 and having its oscillatory circuit provided with the variable condenser 4' 100

for the purpose of adjusting the frequency. Connected to the oscillatory circuit of the device 26 is a conductor 27 leading to the grid of an amplifier 28. The anode of the 5 oscillation generator 26 is connected to the anode conductor 10 through a radio frequency choke 29, and likewise the anode of the amplifier 28 is connected through the primary winding to the transformer 25 and 10 choke coil 49 to the conductor 10 both of said anodes being supplied with potential from the source 9. Condensers 46 and 45 connected between the respective anode circuits of the generator 26 and amplifier 28 and 15 the cathode conductors and likewise condensers 48 and 47 similarly connected in the circuits of the generator 1 and amplifier 5, are provided together with the choke coils 29, 49, 11 and 12 for the purpose of preventing 20 undesirable interaction of the various anode circuits. The transformer 25 comprises the output transformer of the amplifier 28 and has its secondary winding connected in the grid circuit of the modulators 20, 21 and 22 25 as has been explained above.

It may thus be seen that the grids of the modulator tubes 20, 21 and 22 are impressed with polyphase voltages from the secondary windings of the transformer 17, 18 and 19 30 and also with single phase voltages from the secondary winding of transformer 25.

The output circuits of the modulators 20, 21 and 22 are connected through reactances 30, 31 and 32 to the primary of the three 35 phase transformer 33. It will be noticed from the drawing that the transformer 33 has six primary windings, two disposed upon each leg of a three phase core. These windings are connected in a three phase Y connection 40 two windings upon separate legs of the output transformer being connected in series in each phase of the Y. The anode potential for the modulators 20, 21 and 22 is supplied from a source of potential 35 which is connected between the cathode circuit 7 and the 45 neutral conductor 34 of the Y. The primary coils upon each respective leg of the transformer 33 are so connected that the direct currents flowing through them produce opposing magneto motive forces in the core. Thus the current flowing in the anode circuit of the device 21 will flow from cathode conductors 7 through the source 35, conductor 34, primary winding 36 in a direction to produce a flux as indicated by the arrow, primary 50 36, reactance 31 to the anode of the device 21. Likewise current flowing in the anode circuit of the modulator 20 will flow from cathode conductors 7 through the source 60 35, conductor 34, primary winding 37, primary winding 38 in a direction to produce a flux as indicated by the arrow, reactance 30 to the anode of the device 20. It will be noticed that the magneto motive forces produced by current flowing in the windings 55 35

and 38 are in opposed relation. By this means the direct current flux in each of the legs of the transformer is neutralized thus increasing the transformer reactance and enabling a smaller transformer to be employed. This 70 connection also has the effect of eliminating single phase components which appear in the output circuits of the modulators and also certain of the harmonic frequencies. For the purpose of further eliminating harmonics 75 and other undesirable components, including currents having the frequencies of the oscillators 1 and 2, a filter is provided in the output circuit of the modulators which comprises the above mentioned reactances 30, 31 and 32 connected in series with each of the polyphase conductors and condensers 39, 40, 41, 42, 43 and 44 connected between each of the polyphase conductors of the output circuit and the cathode conductors 7. These condensers and reactances are so arranged as to form a suitable and well known type of filter circuit between the modulators and the primary of the output transformer. Alternative designs of filter may of course be used. 80

In the operation of my device as a generator of polyphase currents of audio frequency I adjust the frequency of the oscillator 1 by means of the condenser 4 at some definite value. This value is preferably in the radio frequency range. I then adjust the frequency of the oscillation generator 26 at a value differing from that of the generator 1 by the frequency of the oscillations which are to be produced. The frequency of this latter generator may be varied throughout any desired range by means of the condenser 4'. Both of these frequencies are supplied to the polyphase circuit including the grids of the modulators 20, 21 and 22. Thus both single phase 95 and polyphase currents appear in this circuit. In the output circuit of the modulators 20, 21 and 22 appear, among others, polyphase currents having a frequency equal to the beat frequency between the currents produced by 100 the oscillation generators 1 and 26, and also currents having the sum frequency of these two currents. Preferably in varying the frequency of the oscillations produced in the 105 output circuit the frequency of the oscillation generator 1 is left constant and that of the generator 26 is varied by means of the condenser 4'. By this means currents flowing in the phase splitting circuits 14, 15 and 16 are of constant radio frequency thus enabling an effective splitting of the phases at all 110 frequencies of the output current and by means of inductance and capacity used in these circuits which are of constant value and comparable in size with those of the usual radio frequency channel. Since there are no tuned or resonant circuits in the output circuit of the modulators 20, 21 and 22 the 115 frequency of the output currents flowing 120

therein may readily be varied by adjusting the single condenser 4'.

Thus it may be seen that I have produced an oscillation generator of the polyphase type in which, among other advantages, the output circuit is free from tuned or resonant circuits, in which the phase splitting circuit may be left in one condition throughout the entire frequency range and in which the frequency may be readily varied. Furthermore, it may be seen that my generator is adapted to the generation of polyphase audio currents, and while I particularly mention its utility in that connection, it will, of course, be understood that it is by no means limited thereto since it is also adapted to the generation of currents having frequencies throughout the frequency spectrum. As is well understood in the art currents having a frequency equal to the sum of the frequencies of the currents flowing in the grid circuit of the modulator tubes will appear in the output circuit as well as those of the difference frequency, and I wish it to be understood that the generation of currents of the sum frequency is fully contemplated by my invention. In adapting my circuit to the generation of currents having the sum frequency the filter circuit utilized in the output circuit of the modulators will be varied in a manner well-known in the art, and which need not be here described.

What I claim as new and desire to secure by Letters Patent of the United States, is:—

1. In a generator of polyphase currents of adjustable frequency, a polyphase circuit adapted to be supplied with polyphase currents of constant frequency and single phase currents of adjustable frequency, means associated with said polyphase circuit for producing polyphase currents having a frequency equal to the beat frequency between said polyphase currents and said single phase currents and means for eliminating from the output of said generator currents having a frequency equal to or greater than the lower frequency of the mentioned single phase and polyphase currents.

2. In a generator of polyphase currents of adjustable frequency, a polyphase circuit adapted to be supplied with polyphase currents of constant frequency and single phase currents of adjustable frequency, modulating means for said currents connected in each phase of said polyphase circuit, each of said modulating means having an output circuit and filtering means connected in said output circuit for eliminating undesired components including said polyphase currents of constant frequency.

3. In a generator of polyphase currents of adjustable frequency, a polyphase circuit, means for impressing polyphase currents of constant frequency on said polyphase circuit, means for impressing single phase currents

of adjustable frequency on said polyphase circuit, modulators associated with said polyphase circuit for producing a beat note between said single phase and polyphase currents and means for separating said beat note from undesired components including said polyphase currents of constant frequency.

4. In a generator of polyphase currents of adjustable frequency, a generator of single phase currents of constant frequency having an output circuit, means in said output circuit for converting said single phase currents into polyphase currents, a polyphase circuit having said polyphase currents impressed thereon, a second generator of single phase currents of adjustable frequency, means for impressing said single phase currents upon each phase of said polyphase circuit, modulating means adapted to be supplied with current from said polyphase circuit and means for eliminating undesired components including currents of said constant frequency from the output currents of said modulating means.

5. In a polyphase oscillation generator, a generator of single phase oscillating currents having an output circuit, means in said output circuit for converting said single phase currents into polyphase currents, a polyphase circuit having said polyphase currents impressed thereon, a second generator of single phase oscillating currents of frequency differing from the frequency of said polyphase currents, means for impressing said single phase currents upon each phase of said polyphase circuit, means connected in each phase of said polyphase circuit for modulating said currents and means for eliminating from the output of said modulating means currents of frequency greater than that of currents produced by either of said generators.

6. In a polyphase oscillation generator, a generator of single phase oscillating currents having an output circuit comprising a plurality of branches, said branches being adapted to conduct currents having a desired phase relation, a polyphase circuit, each phase of said polyphase circuit having current impressed thereon from a corresponding branch of said output circuit, a second generator of single phase oscillating currents of frequency differing from the frequency of the mentioned oscillating currents, means for impressing said single phase currents upon each phase of said polyphase circuit, vacuum tube modulators associated with said polyphase circuit and means associated with the output circuits of said modulators for cancelling the single phase components of said first generator.

7. In a polyphase oscillation generator, a generator of a single phase oscillating currents, an output circuit for said single phase generator, including a plurality of branches,

said branches being adapted to conduct currents having a definite phase relation, a polyphase circuit, each phase of said polyphase circuit having current impressed thereon from a corresponding one of said branches, means for impressing currents of a frequency differing by amounts within the audio range from said polyphase currents upon said polyphase circuit, means for varying the frequency of currents impressed on said circuit by said last means, and means associated with said polyphase circuit for producing polyphase currents having a frequency equal to the difference between the frequencies of said two currents.

8. In a polyphase oscillation generator, a generator of single phase oscillating currents, an output circuit for said single phase generator including a plurality of branches, said branches being adapted to conduct currents having a definite phase relation, a polyphase circuit, each phase of said polyphase circuit being associated with a corresponding one of said branches and adapted to be impressed with current therefrom, means for impressing single phase currents of frequency differing by amounts within the audio range from said polyphase currents upon said polyphase circuit, means for varying the frequency of currents supplied by said last means, and modulating means associated with said polyphase circuit.

9. In a polyphase oscillation generator, a plurality of single phase radio frequency oscillation generators which differ in frequency by an amount within the audio range, one of said radio frequency oscillation generators having an output circuit comprising a plurality of branches, said branches being adapted to conduct currents of desired phase relation, a polyphase circuit, each phase of which is supplied with current from a corresponding branch of said output circuit, means for supplying single phase current from another of said generators to said polyphase circuit, a plurality of electron discharge modulators for producing a beat frequency between said currents, each of said modulators having a grid and anode which are connected in one phase of said polyphase circuit and means connected in the anode circuit of said modulators for separating currents of said beat frequency from the radio frequency components of the output from said modulators.

10. In combination, a generator of single phase current of constant frequency having an output circuit, means in said output circuit for converting said single phase current into polyphase currents, a polyphase circuit having said polyphase currents impressed thereon, means for supplying single phase current to each phase of said polyphase circuit, an electron discharge modulator for said single phase and polyphase currents connected in each phase of said polyphase cir-

cuit, each of said modulators having an anode, a polyphase transformer having a plurality of primary windings on each leg and an anode connection for each of said modulators including a winding on each of a plurality of legs of said transformer whereby undesired current components are eliminated.

11. In combination, a generator of single phase oscillations of constant frequency, a polyphase circuit, means for producing polyphase oscillations from said single phase oscillations and supplying said polyphase oscillations to said circuit, a second generator of single phase oscillations of frequency differing from said polyphase oscillations by an amount within the audio range, means for varying the frequency of oscillations produced by said second generator, and means associated with said polyphase circuit for producing polyphase oscillations having a frequency equal to the difference in frequency of oscillations produced by said generators.

In witness whereof, I have hereunto set my hand this 16th day of March, 1927.

CHARLES J. YOUNG.
